(57) **CLAIM**

The ornamental design for an aircraft carrier, as shown and described.

DESCRIPTION

FIG. 1 is a top-front-left perspective view of an aircraft carrier showing my new design;

FIG. 2 is a bottom-rear-right perspective view thereof;

FIG. 3 is a front elevated view thereof;

FIG. 4 is a rear elevated view thereof;

FIG. 5 is a top plan view thereof, wherein the aircraft carrier is shown with an exemplary aircraft deck layout;

FIG. 6 is a bottom plan view thereof;

FIG. 7 is a right elevated view thereof;

FIG. 8 is a left elevated view thereof; and,

FIG. 9 is an enlarged cross-sectional view taken along line 9-9 in FIG. 8, wherein the opposite direction is a mirror image thereof.

The broken lines showing of an aircraft deck layout in FIG. 5, the broken lines showing of a bow and a stern in FIGS. 1-8, and the broken lines showing of an aircraft inner structure in FIG. 9 are included for the purpose of showing environmental structure and form no part of the claimed design.
